GOLF PUTTER HEAD

Raymon W. Cook, 102 W. Rampart, Apt. P102,
San Antonio, Tex. 78216

Filed Sept. 29, 1972, Ser. No. 293,522

Term of patent 14 years

Int. Cl. D21—02

U.S. Cl. D34—5 GH

FIG. 1 is a front elevational view of a golf putter head showing my new design;

FIG. 2 is a front end view of FIG. 1;

FIG. 3 is a top plan view of FIG. 1;

FIG. 4 is a bottom plan view of FIG. 1;

FIG. 5 is a rear elevational view of FIG. 1; and

FIG. 6 is a sectional view taken on the line 6—6 of FIG. 5.

I claim:

The ornamental design for a golf putter head, as shown.
